UNITED STATES PATENT OFFICE

162,582

PAPER CUP DISPENSER

Samuel Scherr and French E. Smith, Akron, Ohio, assignors to Charles C. Hall, Akron, Ohio

Application January 28, 1950, Serial No. 7,557

Term of patent 14 years

(Cl. D52—3)

To all whom it may concern:

Be it known that we, Samuel Scherr, a citizen of the United States, residing at Akron, in the county of Summit and State of Ohio, and French E. Smith, a citizen of the United States, residing at Akron, in the county of Summit and State of Ohio, have jointly invented a new, original, and ornamental Design for Paper Cup Dispenser, of which the following is a specification, reference being had to the accompanying drawing, forming part thereof.

Fig. 1 is a front elevation of the paper cup dispenser showing our new design;

Fig. 2 is a side view;

Fig. 3 is a back view;

Fig. 4 is a top view; and

Fig. 5 is a bottom view.

We claim:

The ornamental design for a paper cup dispenser, as shown.

SAMUEL SCHERR.
FRENCH E. SMITH.
